Inventor

Henry R. Taylor

United States Patent Office.

IMPROVED REFRIGERATOR.

HENRY R. TAYLOR, OF ROXBURY, MASSACHUSETTS.

Letters Patent No. 60,281, dated December 4, 1866.

SPECIFICATION.

TO ALL WHOM IT MAY CONCERN:

Be it known that I, HENRY R. TAYLOR, of Roxbury, in the county of Norfolk, and State of Massachusetts, have invented certain improvements in Refrigerators, of which the following is a full, clear, and exact description, reference being had to the accompanying drawings, making part of this specification, in which—

Figure 1 is a front elevation of my improved refrigerator.

Figure 2 is a transverse vertical section of the same, on the line *z z* of fig. 1, looking in the direction of the red arrow.

Figure 3 is a longitudinal vertical section of the same, on the line *y y*, of fig. 2.

Refrigerators, as at present constructed, are objectionable for the reason that when opened for the reception or removal of the meat or other articles the ice receptacle is exposed to the external air, causing a waste of the ice. My invention has for its object to overcome this difficulty, and consists in a refrigerator provided with a drawer for containing the meat, &c., which when pulled out entirely closes the opening in which it slides, and prevents the entrance of the external air; that within the refrigerator being thus kept constantly cool and unchanged, as required. To enable others skilled in the art to understand and use my invention, I will proceed to describe the manner in which I have carried it out.

In the said drawings, A is the outer wall or casing, B the inner wall, and *a* the air space between the two. C is the ice receptacle, which is closed by a door, D, and occupies the greater part of the horizontal area of the upper portion of the refrigerator; a pipe, *b*, at the rear serving to carry off the moisture, thus keeping it perfectly dry. Adjoining the ice receptacle, C, and separated therefrom by a vertical partition, E, is a small cooling chamber, F, which is closed by a door, G, and is provided with a shelf, *c*, the partition, E, being perforated with holes, *d*, for the passage of the cold air from the ice receptacle, C. The bottom of the chamber, F, is perforated with holes, *e*, through which the cold air descends into the lower portion of the refrigerator, which is occupied by a drawer, H; furnished with racks or shelves, which forms the main refrigerating chamber, for containing the meat or other articles. The drawer, H, is constructed with a sliding-piece, I, on each side, (seen also in red in fig. 2,) by which it is supported, and when pulled out to its full extent, prevented from sagging down, as is more fully described in Letters Patent of the United States granted to me on the 27th day of April, A. D. 1858, and on the 21st day of February, A. D. 1860. These sliding-pieces, I, together with the pieces J, on the inside of the refrigerator, which hold them in place, serve to close the spaces on each side of the drawer, H, and prevent the entrance of the external air. *f* is a strip which is bevelled or wedge-shaped in cross-section, and extends across the under side of the drawer, H, so that when the latter is pulled out to its full extent the strip *f* will strike against a correspondingly bevelled strip, *g*, on the inside of the bottom of the refrigerator, and raise the drawer slightly, so that its upper edge, *h*, which is bevelled, will strike against the longitudinal strip, *i*, above it, and the entire space around the drawer, is thus effectually closed, as required, so that when pulled out for the reception or removal of meat, &c., it will be impossible for the external air to enter and raise the temperature of the air within the refrigerator, which is thus kept constantly cool, thereby preventing any unnecessary waste of the ice. The doors, D G, and also the inside of the projecting portion of the drawer, H, are edged with cloth or felt, to more effectually exclude the warm air, and the strips, *f g i*, and upper edge, *h*, of the drawer, H, may also be covered with the same material if desired. The wedging of the strips, *f g*, is relieved as soon as the drawer is pushed in slightly, after which it will slide with the greatest ease. *j* is an opening into the ice chamber, C, which serves to ventilate the interior of the refrigerator.

The above described refrigerator possesses many advantages over those now in general use, is of simple construction, and may be furnished at a moderate cost.

Claim.

What I claim as my invention, and desire to secure by Letters Patent, is—

A refrigerator provided with a drawer so arranged that when pulled out it will close the opening in which it slides and exclude the external air from the interior of the refrigerator, substantially as described.

HENRY R. TAYLOR.
